UNITED STATES PATENT OFFICE.

AUGUST C. SCHENK, OF VANCOUVER, WASHINGTON.

PLOWSHARE.

1,358,584.

Specification of Letters Patent.

Patented Nov. 9, 1920.

Application filed November 14, 1919. Serial No. 337,975.

To all whom it may concern:

Be it known that I, AUGUST C. SCHENK, a citizen of the United States, residing at Vancouver, in the county of Clarke and 5 State of Washington, have invented new and useful Improvements in Plowshares, of which the following is a specification.

The object of my present sole invention is the provision of a construction that is 10 simple, compact and durable, and in which the parts are so relatively arranged that a share point may be expeditiously and easily applied to and disconnected from a share body without the employment of any extra- 15 neous connecting elements and without the assistance of any tools other than an ordinary hammer or something that may be used in place of the same.

To the attainment of the foregoing, the 20 invention consists in the improvement as hereinafter described and definitely claimed.

In the accompanying drawings, hereby made a part hereof:

Figure 1 is a side elevation showing a 25 mold board equipped with my novel share; the share point being arranged as locked in working position to the share body.

Fig. 2 is an inverted plan view of the share body with the share point removed.

Fig. 3 is a side elevation of the point, removed.

Fig. 4 is an end elevation of the share body *per se*.

Fig. 5 is an end elevation showing the 35 share point removed.

Figs. 6 and 7 are transverse sections taken in the planes indicated by the lines 6—6 and 7—7, respectively, of Fig. 1.

Similar numerals of reference designate 40 corresponding parts in all of the views of the drawings.

In accordance with my invention, the share body 1 is bolted to a mold board 1^a and is provided in its lower edge with a 45 channel 2 which extends throughout the length of the body, and is open at its ends. In the said channel and fixed with respect to the walls thereof are keepers 3. The lower edges of the said keepers are preferably flush 50 with the lower edges of the channel walls.

My invention contemplates the provision of a plurality of the share points 4 and the use of the said share points in succession on the body 1. The share point is preferably 55 of the general form illustrated, and is characterized by a plurality of longitudinal

spaced fastener lugs 5 on the upper edge of the point and in the longitudinal center thereof; the said lugs 5 being of less width than the upper edge of the point 4, so as to 60 enable the said upper edge to bear solidly against the lower edges of the walls of the channel 2 in the body 1 when the share point is positioned for use. Each of the said fastener lugs 5 is provided with a rearwardly 65 directed tongue 6, spaced from the upper edge of the point 4 and having its lower side, by preference, declined forwardly as illustrated.

In the practical use of my improvement, 70 the share body 1 is arranged at and connected to the lower edge of the mold-board, and the fastener lugs are sheathed in the channel 2 of the body 1, so that the fastener lugs 5 rest in rear of the keepers 3. Then 75 when the upper edge of the share point is adjacent to and in substantial parallelism with the lower edge of the body 1, the point 4 is driven rearwardly by hammer blows or the like imposed on its forward end, when 80 the tongues 6 of the fastener lugs will ride over the keepers 3 and thereby effect connection of the point 4 to the body 1. It will also be observed that the wedging action of the tongues of the fastener lugs on the keepers 3 will have the effect of drawing the upper edge of the point 4 snugly against the lower edge of the body 1, with the result that the body and point will be rendered 85 practically continuous, and at the same time 90 casual disconnection of the point from the body 1 will be precluded. Notwithstanding this, however, it will be observed that after hammer blows are applied to the rear end of the share point to disengage the tongues 95 6 of the fastener lugs 5 from the keepers 3, the fastener lugs may be readily withdrawn from the channel 2 in the body and the point 4 removed to give place to a fresh point.

Having described my invention, what I 100 claim and desire to secure by Letters-Patent, is:

1. In combination with a body having a longitudinal channel in its lower edge and also having keepers fixed in said channel 105 at intervals in the length thereof, a share point abutting at its upper edge against the lower edges of the channel walls of the body and having in upright position on the longitudinal center of its said upper edge longitudinal vertical fastener lugs of reduced thickness sheathed in the channel and pro-

vided with rearwardly extending tongues the lower edges of which are forwardly declined, whereby the tongues in conjunction with the keepers afford a wedging action.

- 5 2. In combination with a share body adapted to be connected to a mold-board and having a longitudinal channel in its lower edge and keeper means in said channel, a share point solidly abutting at its

upper edge against the lower edge of the 10 body and having fastener means extending upwardly from its upper edge and sheathed in the channel of the body and coöperating with the keeper means thereof to detachably hold the share point in working position to 15 the body.

In testimony whereof I affix my signature.

AUGUST C. SCHENK.
